UNITED STATES PATENT OFFICE.

JOHN HISKEY PALM, OF MINNEAPOLIS, MINNESOTA.

CIRCULAR SAWING MACHINE.

SPECIFICATION forming part of Letters Patent No. 326,583, dated September 22, 1885.

Application filed January 6, 1885. (No model.)

To all whom it may concern:

Be it known that I, JOHN HISKEY PALM, a citizen of the United States, and a resident of Minneapolis, in the county of Hennepin, and in the State of Minnesota, have invented certain new and useful Improvements in Sawing-Machines, of which the following is a specification.

Figure 1 is a semi-sectional elevation of the right-hand side of the machine, and Fig. 2 an elevation from the left-hand side of the machine, these two views showing the machine arranged with an oscillating saw-frame and a curved feed-plate. Fig. 3 represents a portion of the upper part of the frame and saw-operating mechanism, with the saw-frame arranged to slide horizontally and with a horizontal feed-plate. Fig. 4 is a front elevation, and Fig. 5 is a plan view, of the construction shown in Figs. 1 and 2. Fig. 6 represents a detached detail of the lower bearing of the oscillating frame. Figs. 7 and 8 are views of portions of the lower ends of the oscillating saw-frame.

25 A is the main frame, which may be constructed in any suitable manner of wood or metal, or partially of wood and partially of metal, and with a shaft, B, journaled in bearings C' C² on its rear side near the top. Beneath the shaft B, in the same bearings C' C², is journaled another shaft, D', the latter adapted to be driven from the shaft B by a pinion, a, and a gear, b, the shaft D' thus running at a lower speed than the shaft B.

35 E' E² are two shaft-boxes attached to the lower horizontal sections of the frame A, and having a shaft, F, journaled therein and running across the frame, and provided on its center with a pulley, G', the shaft being held in place in the boxes by suitable caps, E³ E⁴.

E⁵ is a yoke or bar connecting the boxes E' E², so that they will always retain their position and render the adjustment of the saw more easy, as hereinafter explained.

45 Cast upon the inner edge of each of the boxes E' E² are hubs H' H², (see Fig. 6,) which surround the shaft F, and are adapted to serve as pivots or journals to the lower ends of the saw-frame I', so that the latter may swing around the shaft F as a center. The shaft F is operated from the power-shaft B by means of pulleys F' and B', mounted, respectively, on said shafts, and a suitable connecting-belt. The pulley F' is of a much smaller diameter than

the pulley B', whereby the shaft F is rotated at a much higher speed than the power-shaft B.

The saw-frame consists of a lower section, I', and an upper section, I², the two sections being formed to lap over each other and secured together by bolts d'. Each section will usually be formed of an open lattice-like casting to render them lighter, while at the same time retaining their strength. The upper section, I², will be provided on its top with boxes e' e², carrying the saw-mandrel K' and small pulley G², the latter in line with and adapted to be driven by a belt, G³, from the pulley G'.

K' is the saw, which is mounted in the ordinary manner on the end of the mandrel K', as shown.

i' is a screw, tapped through the cross-bar i² of the lower frame, I', and with its upper end in contact with the cross-bar i³ of the upper frame, I², so that when screwed up it will elevate the frame I² and tighten the belt G³. The bolts d' d' will fit through slots in one of the frames I' or I², so that the frames will slide upon each other when adjusted by the screw i'. Then by tightening up the screws d' d' the frame may be held rigidly together.

K is a curved plate concentric to the shaft F and attached by one end, at m, to the upper part of the frame I², and running backward and downward beneath a roller, D², on the shaft D'.

D³ is another roller on a shaft, D⁴, journaled in lugs D⁵ D⁶ on the bearings C' C², and parallel with the shafts D' and B. The journals h' h² of this shaft D⁴, where they pass through the lugs D⁵ D⁶, are eccentric to the main portion of the shaft, so that when the shaft is oscillated in its bearings the roller D³ will be raised and lowered to throw the plate K upward against the roller D² or release it from contact therewith, as hereinafter set forth.

L' is a bracket attached to the frame A in any suitable manner, and having a small drum, L², secured in its outer end by a thumb-screw, L³, so that the drum may be firmly held in the bracket at any desired point in its revolution.

L⁴ is a spring secured by one end to the upper frame, I², and having a cord or wire, L⁵, connecting its other end with the drum L². By this simple arrangement, if the drum L² be re-

ved, the cord will be wound up thereon or unwound therefrom and the tension of the spring increased or decreased, as desired, and by means of the thumb-screw L^1 this tension 5 may be retained by holding the drum fixed upon the bracket L^1 .

M' is a small lever secured by one end to one of the journals h' or h^2 of the shaft D^4 and connected by a rod, M^2 , to a foot-lever, M^3 , 10 the latter pivoted at M^4 to the lower side of the frame A , as shown.

M^5 is a spring connecting the lever-arm M' with the frame A to hold the lever-arm down in place and return the treadle to its former position when released from the pressure of the 15 foot of the operator.

The lever M' and also the rod M^2 and lever M^3 are provided with a number of holes where the pivots n' n^2 pass through them, so 20 that they may be adjusted to regulate their action.

N' is the table on which the lumber to be sawed is placed, and is pivoted or hinged to the frame A at N^2 , and provided with a rest 25 or stop, N^3 , at the other end. The table is arranged in a downwardly and backwardly inclined position, as shown, and rests by its lower end upon two or more cams, N^4 N^5 , upon 30 a shaft, N^6 , journaled in suitable bearings across the frame A , as shown. On one end of this shaft N^6 is a lever, N^7 , having a spring-dog, N^8 , adapted to catch in teeth in a segment, N^9 , on the frame A . The shaft N^6 may be thus revolved to any extent to cause the 35 cams N^4 N^5 to raise the table N' , and then, by means of the dog N^8 and toothed segment N^9 , the table may be supported at any height of elevation.

A circular saw works to the best advantage 40 if it is so set with reference to the lumber being cut that its upper edge will just cut through the lumber; hence by my arrangement of the adjustable table I can very quickly and easily adjust the table to the thickness 45 of the lumber, and thus accomplish the above results.

In Figs. 1, 2, 4, and 5 the saw-frame is shown arranged to be oscillated upon its lower shaft; but I do not wish to confine myself to 50 this precise form of construction, as I am aware that it may be arranged to move in a substantially horizontal plane and with the plate K in a similar position, as shown in Fig. 3.

The construction and operation is substantially the same in both cases, however, 55 the only difference being that the relative positions of the shafts B D' and their rollers D^2 D^3 will have to be altered slightly, as shown in Fig. 3.

Having thus described my invention, what I claim as new is—

1. In a sawing-machine, a saw-table, a traveling saw-carrying frame beneath said table, and a circular saw mounted on said frame and 60 adapted to said table, in combination with a feed-plate attached at one end to said saw-frame, a constantly-rotating friction-roller, an

eccentric shaft, an idle-roller mounted on said shaft, said rollers being located on opposite sides of said feed-plate, a lever-arm secured at one end to said eccentric shaft, a pivoted foot-treadle, and a rod connecting said foot-treadle with the free end of said lever-arm, substantially as and for the purpose herein set forth. 70

2. In a sawing-machine, a swinging saw-carrying frame, a saw mandrel mounted thereon, a saw and a small pulley, G^2 , on said mandrel, and a feed-plate and retracting-spring attached to said saw-frame, in combination with a power-shaft, B , a small pinion, a , and a large pulley, B' , on said shaft, a second shaft, D' , mounted beneath said power-shaft, a friction-roller, D^2 , on said shaft D' , a large pinion, b , on said shaft D' , which meshes 80 with the pinion a , an eccentric shaft, D^4 , mounted beneath said shaft D' , a loose friction-roller, D^3 , on said shaft D^4 , said rollers D^2 D^3 being adapted to said feed-plate, a shaft, F , mounted in the bearings of the swinging saw-frame, 90 small pulley F' and large pulley G' on said shaft F , which transmit rotary motion from the pulley B' on the power-shaft to the saw-mandrel by suitable belting, substantially as set forth. 95

3. A swinging frame carrying a circular saw, in combination with a curved feed-plate concentric with the axis of said frame and rigidly attached thereto, and mechanism which acts on said plate and thus moves said frame, substantially as set forth. 100

4. A traveling saw-frame and mechanism which is adapted to move said frame in one direction, in combination with a tension-roller, a set-screw which, when set, prevents the 105 rotation of said roller, a spring secured at one end to said saw-frame and adapted to move said frame in a direction opposite to the aforesaid moving mechanism, and a cord which connects the opposite end of said spring with said tension-roller, substantially as set forth. 110

5. The combination of the power-shaft F' , the pulley G' , carried thereby, the swinging saw-carrying frame, the saw-mandrel K , mounted on said frame, the pulley G^2 , carried by said mandrel, the belt G^3 , connecting said pulleys G' G^2 , said saw-carrying frame being vertically divided into two overlapping sections, I' I^2 , said sections being provided with vertically-extending slots, bolts d' d^2 , passing through said slots and connecting said sections, cross-bars i' i^2 , located on the sections I' I^2 , respectively, and a screw, i , tapped through one of said sections and adapted to 120 bear against the other section, substantially as set forth. 115

In testimony whereof I have hereunto set my hand in the presence of two subscribing witnesses.

JOHN HISKEY PALM.
